CLAIM

The ornamental design for the member for coupling cabinets, as shown and described.

DESCRIPTION

FIG. 1 is a front, top and right side perspective view of a member for coupling cabinets showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a reference view showing it in use.

The broken line showing of the cabinets is included for the purpose of illustrating environmental structure and forms no part of the claimed design.
